UNITED STATES PATENT OFFICE.

AUGUST E. ZOCK, OF TOLEDO, OHIO, ASSIGNOR, BY MESNE ASSIGNMENTS, TO
ARCHIBALD B. CREPS, OF MAUMEE, OHIO.

AGRICULTURAL TRACTOR.

1,033,976.

Specification of Letters Patent. Patented July 30, 1912.

Application filed May 23, 1908. Serial No. 434,613.

To all whom it may concern:

Be it known that I, AUGUST E. ZOCK, a citizen of the United States, and a resident of Toledo, in the county of Lucas and State of Ohio, have invented a certain new and useful Agricultural Tractor; and I do hereby declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention relates to motor trucks, and particularly to those adapted for use as agricultural tractors, wherein the power is at times applied for propelling the machine and at other times for operating another 20 machine or apparatus. This invention is not, however, limited to such use, but may be used in any connection for which it may be adapted or appropriate.

The object of my invention is the provision of an improved and highly efficient 25 machine of the class, which is simple, strong and durable in its construction, easy of operation, and inexpensive of manufacture, thus enhancing its practicability and commercial value.

A further object of my invention is the provision of simple and improved means for controlling the lowering or raising of 35 the push-bars and the simultaneous throwing of the crank-shaft to which they are attached into or out of commission with the actuating mechanism, as the case may be.

A further very important object of my invention is the provision, in motor-trucks 40 or other vehicles having front and rear drive wheels, of an improved connection between the steering-wheels and the motor jack-shaft, which will obviate the objections heretofore raised to the use of gear connections between such parts.

Further advantages of my invention as well as the operation, construction and arrangement of the parts of the same are fully described in the following specification, and a preferred embodiment of the 50 same illustrated in the accompanying drawings, in which,

Figure 1 is a plan view of the machine embodying my invention with the body removed. Fig. 2 is a front view thereof. Fig.

3 is a longitudinal section of the same. Fig. 4 is a face view of the guide-plate for the push-bars. Figs. 5 and 6 are plan and side details of the mechanism controlling the raising and lowering of the push-bars and the throwing of the same into or out of connection with the driving means, and Fig. 7 is an enlarged view of the front end of the vehicle.

Referring to the drawings, X designates 65 the frame of the machine on which the body or platform is mounted. This frame is supported by front and rear axles Y and Z and carried by wheels Z', the front pair of which are mounted on the customary pivoted studs or spindles, connected together in the usual manner. The arrangement is preferably such that all four wheels act as drivers, the rear wheels being shown as chain driven and the front wheels as driven by a form of pin 70 gearing, which latter forms a part of my present invention. In addition to these drives a push-bar drive is also provided, which will be hereinafter more fully described.

The power shaft of the machine is designated at H and may be driven by any suitable engine. This shaft is mounted in suitable bearings lengthwise of the frame at the middle thereof, and is provided with a shifting-gear C by means of which either the operating mechanism or the propelling mechanism may be driven. The former has a gear E on a shaft I, which shaft is mounted in suitable bearings above the shaft H and carries a pulley F to which a belt may be applied or from which power may be communicated in any other suitable manner for driving any kind of machinery. A shifting 85 gear C in one direction on its shaft 90 moves it into mesh with the gear E.

The propelling mechanism is driven through a gear D with which the gear C may engage by shifting the same in the opposite direction to that required to throw it 100 into mesh with the gear E. The gear D is mounted on a longitudinal shaft H² which has universal joints 3, and which extends forwardly and has connection with the jack-shaft 4 of the front driving mechanism through the medium of a suitable differential mechanism T. The jack-shaft 4 is provided at its ends with pinions Q which engage with pinions S mounted on the upwardly extending ends of the pivots of the 105

front or steering wheel knuckles, and the pinions S mesh with larger gears M secured to the inner sides of the front wheels Z'.

The driving of the front or steering wheels of vehicles by the use of two miter pinions and a bevel gear or by three bevel gears of different sizes has heretofore been found impractical, due to the fact that it is mechanically impossible to drive a bevel gear from a shaft which is arranged out of alinement with the axis of that gear through the medium of two miter gears or two bevel gears of different size than the driven gear, without distorting the angle of the face of the teeth of such driven gear. To overcome these objections as well as others incident to the use of gears of this character in wheel driving mechanisms, I have adopted gears and pinions having ball-end peg-cogs or teeth which permit a series of gears corresponding to bevel or miter gears of any size to perfectly mesh together and also facilitate a turning of the wheel-gear around the axis of the meshing gear when making a turn. A further very important feature incident to the use of gears of this type in driving mechanism for vehicles is that any mud gathering between the teeth thereof is easily forced out by the action of the meshing teeth, whereas with the use of gears of the bevel or miter type, mud will continue to accumulate between the teeth of the same and cause the meshing gears to spread or crowd away from each other.

The rear wheels are driven by means of a beveled gear Y' on the rear end of the shaft H², which meshes with and operates a beveled gear and differential gear V on a jack or cross-shaft R, which has at its opposite ends sprockets W', which drive large sprockets W² on the rear wheels by means of sprocket-chains W³. The shaft R also has a spur-gear W, which, through an intermediate shifting-pinion L, on a stub-shaft P, drives a gear N on one end of a crank-shaft J. This crank-shaft is mounted transversely of the frame and is shown in the present instance as having four cranks set on quarters to each of which the forward end of a push-bar A connects. Each of these push-bars is provided at its foot or rear end with a conical block A' which has its small end forward and a spur A² projecting centrally from its rear or large end, which spur has its rear or pointed end preferably curved downwardly, as shown, to facilitate a firm engagement of the same with the surface over which it is traveling when in action. The particular shape of the blocks A' not only enables such blocks to work well on soft ground, by giving a large or blunt pushing surface, but also facilitates

an easy and quick withdrawal of such blocks from soft ground, due to the wedge formation of the blocks forcing the same quickly to the surface as the push-bars advance. This form of blocks also prevents a gathering and clogging of soil upon the same.

The push-bars A trail under the rear of the machine and work through vertically elongated openings G' in a guide-plate G, which is suspended beneath the machine transversely thereof by arms G² connected to the shaft J and by hangers G³ connected to arms G⁴ projecting rearwardly from a cross-shaft g which has its ends journaled in the frame to effect a raising or lowering of the guide-plate and push-bars by an oscillation of the hand lever P², which lever has connection with such shaft through a rod p and arm p' on said shaft as best shown in Figs. 5 and 6. The pinion L is also shifted on its shaft when the shaft g is rocked due to an arm g' on said latter shaft and a link or rod r communicating motion to the bell-crunked shifting lever P³, which is fulcrumed to the frame, as at t and has an end in engagement with the hub of the pinion L, as shown. The connection between the shaft g and pinion L is such that the crank-shaft J is thrown into gear with the driving mechanism when the push-bars are lowered to operative position, and vice versa.

I wish it understood that my invention is not limited to any specific construction or arrangement of the parts except in so far as such limitations are specified in the claim.

Having thus described my invention, what I claim as new and desire to secure by Letters Patent, is,—

In an agricultural tractor, the combination of a frame, wheeled axles supporting the same, a propelling mechanism supported by said frame and including a pair of inter-gearred driven shafts, flexible connections between one of the driven shafts and the wheels on one axle, a gear carried by the other driven shaft, a drive shaft, a gear slidable on said drive shaft for engagement with and disengagement from the first-named gear, means for shifting the slidable gear, a shaft journaled in said frame and arranged above and parallel with the drive shaft, and a gear carried by the upper shaft and arranged for engagement with said slidable gear when the latter is disengaged from said first-named gear.

In testimony whereof I affix my signature, in presence of two witnesses.

AUGUST E. ZOCK.
